UNITED STATES PATENT OFFICE.

JOHN WALDHEIM, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Original application filed June 17, 1921, Serial No. 478,231. Divided and this application filed February 5, 1924. Serial No. 690,696.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to improvements in 10 connection with sound-deadening casings or hoods for typewriting machines, the hood being of the same general type as that disclosed in the co-pending application of B. C. Stickney, Serial No. 429,617, filed December 15, 1920 (now Patent No. 1,519,224, dated December 16, 1924), and comprises a sound-deadening casing or hood for enclosing the noise-producing parts of a typewriting machine while the character keys project from 20 the casing or hood, the line-space handle, the carriage-return handle, and the carriage release handle, projecting through a slot in the casing and between slot-closing means extending along said slot, so that the platen may 25 be rotated and the carriage released and returned from the exterior of the casing. This application is a division of my co-pending application, Serial No. 478,231, filed June 17, 1921.

One feature of the present invention is to 30 provide a hood with an opening in the back wall and a releasable cover plate at said opening to enable the hood to be slid over the machine from the front. The front wall 35 of the body part of the hood is provided with a cut-out large enough to clear the keyboard section of the machine and the usual line-lock release key and ribbon-color shift-keys.

Another feature of the invention relates 40 to improved means, comprising a single finger-piece for securing the releasable plate on the hood.

Another feature relates to means to 45 establish the position of the machine on the base upon which it stands, said means comprising metal plates to be engaged by the feet of the machine, said plates being located in holes in the base into which the feet 50 of the machine may readily be inserted.

It is another feature of this invention to provide means whereby the sound-deadening casing and the machine may be held firmly attached to each other.

Still another feature of this invention is 55 the provision of novel means for effectively closing the slot of the casing through which various handles project from the typewriter carriage, to increase its resistance to wear, which is caused by the traveling of the carriage-release handle when the latter is depressed. For this purpose, there is provided a cushion strip and a co-operating yieldably-mounted bar directly opposed to said cushion and in engagement therewith, the 60 carriage-release handle projecting between said strip and bar and pressing the latter when operated.

Other features and advantages will hereinafter appear.

In the accompanying drawings,

Figure 1 is a perspective view of the invention applied to an Underwood standard typewriting machine.

Figure 2 is a fragmentary rear view, 75 showing the slot-closing means at the front of the machine.

Figure 3 is a sectional side elevation of the device shown in Figure 1.

Figure 4 is a rear view of the casing, 80 showing the removable back plate.

Figure 5 is a detail perspective view of the means for holding the casing on the base.

Figure 6 is a detail, showing one of the 85 cups for holding the feet of the typewriting machine.

Figure 7 is a section taken on the line 7-7 of Figure 3, and shows the means for 90 positioning the machine within the casing.

The Underwood standard typewriting machine comprises a main frame 10 and a forward extension 11 of the main frame, in which are positioned banks of keys 12, said keys being carried at the forward ends of key-levers 13, which, when depressed, operate bell-cranks 14 to swing type-bars 15 upwardly and rearwardly and cause types 16, carried thereby, to strike against a platen 17 at the printing point. Said platen is 100 fixed upon a shaft or axle 23, journaled in the end walls 18 of a platen-frame 19 mounted in a carriage 20, having letter-feeding movement, on front and rear rails 21 and 22, fixed to the main frame 10. The platen may be rotated by a knob or finger-wheel 25 fixed to the end of the shaft 23, or by the usual line-spacing mechanism, of which

only the line-space handle 26 is shown. The carriage is provided with the usual pointer 27 operating over scale 28, and may be returned to the right by a finger-piece 29 fixed thereto, or released from the letter-feeding mechanism by a carriage-release lever or handle 30.

The main frame 10 comprises four posts 31, which are provided at their lower ends 10 with rubber feet 32, which rests on metal disks 35 having downwardly-pressed prongs 36, by which the disks are fixed to a base, said disks being in the form of cups to be entered by said feet to aid in positioning 15 the machine on said base. In the present instance, in order to deaden the sound more effectually, the cups are mounted on a pad 20 of felt 37, which, in turn, may be fastened to a base 38 by means to be hereinafter described.

The felt pad 37 forms the immediate base upon which the sound-deadening casing or hood is mounted, in order to seal the lower edges of the hood against escape of 25 sound. By referring to Figure 1, it will be seen that the sound-deadening casing or hood may, therefore, be slid along the base or felt pad 37 and onto the machine from the front thereof, without encountering any 30 obstruction and without requiring the casing to be lowered vertically. To permit the casing to be mounted in this manner, it comprises a cover part 51 hingedly connected at the rear to a body part 52 (Figure 3), said 35 body part comprising a front wall 53, formed preferably integral with side walls 54 and a rear wall 55 extending upwardly a distance above the highest point of the typewriting machine, and provided with an 40 opening 56^a (Figure 4) large enough to permit passage of the machine therethrough, said opening being below the joint of the cover 51 to the body of the casing and being closed by a releasable back plate 45 56. The latter is readily fixed upon, or removed from, the rear wall 55, the back plate being provided with hooks 57 (Figures 4 and 7) adjacent one side edge which engage in slots 58 in the rear wall for mounting 50 the back plate on the wall, said plate being locked to said wall by a slideable latch or bolt 60 mounted on the plate adjacent the other side edge, and having fingers 61 engaging in openings in projections 62 fixed 55 to the rear wall and passing through slots in the back plate. The latch 60 is slidably mounted on the back plate by means of headed studs 63 fixed to the plate and operating in longitudinal slots 64 in the 60 latch, so that the latch may be operated upwardly and downwardly by a finger-piece 65, the upward movement of latch 60 operating to withdraw fingers 61 from engagement with projections 62, to permit 65 the latter to be withdrawn from the slots

in the back plate, so that said plate may be swung rearwardly and lifted off the rear wall by withdrawing hooks 57 from slots 58.

With the back plate 56 removed, the casing is slid along base 38 and pad 37, the forward extension 11 of the main frame entering the rear of the casing, and the latter being moved rearwardly until the forward posts 31 of the main frame contact 70 with abutments or locating devices 70 fixed to the front wall of the casing, the forward extension 11 projecting forwardly through a keyboard opening formed in the front wall 53 and in line with the opening 56^a in 80 the rear wall, permitting the casing to be carried backwardly over the machine by a simple motion. Since the front-to-back dimensions of the machine are small, for compactness, it will be understood that the machine may occupy the front and rear openings simultaneously in assembling the machine with the casing. The back plate is then applied in the manner described above, the machine being held firmly between the 90 abutments 70, fixed to the front wall of the casing and contacting with the forward posts 31 of the main frame, and abutments 71 carried by the back plate and contacting with the rear posts 31 of the main frame. 95

The typewriter carriage is free to operate to the right or left, the body part of the casing being provided with right and left extensions 75 over which the carriage travels, the cover part 51 being of sufficient 100 length to co-operate with the upper edges of the body part, including the extensions. The cover part comprises end walls 76, co-operating with the side edges of extensions 75, a rear wall 77 by which it is hingedly 105 connected (at the line 7, at the right-hand upper part of Figure 3) to the rear wall 55 of the body part, a forwardly-extending and downwardly-inclined ceiling 78 provided with a transparent plate 79 for permitting the typewriting within the casing to be viewed, and a short front wall 80 terminating some distance above the upper edge of front wall 53, so as to leave a longitudinal slot 90 at the front of the machine. 110 Through this slot project the line-space handle 26, carriage-return finger-piece 29, and carriage-release lever 30, so as to permit ordinary operation of the machine without necessitating raising of the cover. 115 It is necessary, however, to close all of the slot not actually occupied by these finger-pieces, in order to prevent transmission of sounds therethrough. For this purpose, two co-operating members 81 and 82 are 120 provided, the former being mounted on the front wall 80 of the cover, and the latter on the front wall 53 of the body part. Member 81 comprises a fold or cushion 83 of sound-deadening material, such as plush, felt or 125 130

soft leather, the upper edges of the fold being clamped between two bars 84 and 85, bolted together to form a single unit, which is mounted on the front wall 80. Co-operating with cushion 83, to close the slot, is a bar 86 in engagement with said cushion and directly opposed thereto. As heretofore described, the various carriage-operating levers project through the slot 90, between cushion 83 and bar 86, and, to permit downward movement of the carriage-release lever, bar 86 must be yieldably mounted. For this purpose, bar 86 may be mounted for bodily movement in a vertical direction by a parallel linkage, which may be like that disclosed in my co-pending application, No. 466,820, filed May 4, 1921 (now Patent No. 1,519,645, dated December 16, 1924) and may comprise bell-crank 87, one near each end of the bar, said bell-cranks being interconnected by a link 88 and pivoted at 89 to brackets 91, fixed to the front wall 53 of the body part of the casing. A return-spring 92 for the bar 86 is connected between one of the brackets 91 and the link 88. Bar 86 is preferably of rigid material, because it is subject to much wear due to the contact therewith of the carriage-release lever, which is pressed against and slides along the bar. A stop 94^a on the bell-crank 87 engages one end of a hole 94 in the bracket 91 to limit the return movement of the bar 86.

To guide the hood laterally when it is slipped over the machine, there are provided guide-bars 93 at the sides of the hood, said guide-bars being secured by screws 93^a which pass through the felt pad 37 and into the base 38. The hood is thus guided, so that it may properly engage with abutments or brackets 100 secured to the base by screws 100^a, said abutments engaging just outside the limits of the back plate 56, so as not to interfere with the attaching of said plate, which is done after the hood has been located by the abutments. Felt pieces 101 may be interposed between brackets 100 and the rear wall 55 to absorb any vibration.

To secure the hood to the base, each side of the hood is provided with a projection or pin 97, said pins engaging under forwardly-projecting fingers 93^b on the forward ends of the guide-bars 93.

Since the hood may become accidentally displaced on the base, it is desirable to provide means to guard against such displacement, and, consequently, retain the pins 97 in engagement with the fingers 93^b. For this purpose, there are pivotally mounted, near the forward ends of the guide-bars 93, latches 95 to engage the pins 97 and hold them under the fingers 93^b. The latches are formed at the forward ends of pivoted bell-crank-levers 96, said latches being operable

by finger-pieces 99 and move against the tension of springs 98. With this arrangement it will be understood that, in order to release the hood from the base, it is merely necessary to push the finger-pieces rearwardly until the latches 95 disengage the pins 97 when the hood may be drawn forwardly. On the other hand, when attaching the hood to the base, it is merely necessary to push the hood rearwardly until arrested by the abutments 100, pins 97 being effective to engage under and raise the latches, the latches snapping behind the pins without any attention on the part of the typist.

While the casing is being slid over the machine, the cover may be held slightly raised, so as to permit the line-space handle 26, the carriage-return handle 29 and the carriage-release handle 30 to extend through the slot 90 at the front of the casing. Interrupted movement of the hood by the slot-closing bar 86 is prevented while it is being slid over the machine, due to the fact that said bar is limited in its upward movement by the stop 94^a, so as not to collide with the forward edges of the various handles on the carriage.

The usual line-lock release-key 105 and the ribbon-color shift-keys 106 project through the opening in the front wall 53, said opening being so formed as to clear said line-lock release-key and the ribbon-color shift-keys, and thus avoiding the necessity of removing the ribbon-color shift-key when the casing is slid over the machine.

The casing may be lined with any suitable sound-deadening material, such as felt.

Variations may be resorted to within the scope of the invention, and portions of the improvements may be used without others.

Having thus described my invention, I claim:

1. A sound-deadening casing for a type-writing machine having a front keyboard extension, said casing having a body comprising a front wall having an opening through which said extension may extend forwardly, and a rear wall having an opening in line with said front opening and sufficiently large to permit passage of the casing rearwardly over said machine, rear wall first, a releasable back for closing said opening in the rear wall, and a cover hinged in rear to said body, the joint between the cover and body being above said opening in said rear wall.

2. A sound-deadening casing for a type-writing machine having a keyboard extension and a carriage having a forwardly-extending finger-piece, said casing comprising a body part and a cover providing therebetween at the front a slot through which said finger-piece may project, said body part comprising a front wall beneath

said finger-piece and having an opening to permit said keyboard extension to project therethrough, and a rear wall having an opening in line with the front opening and 5 sufficiently large to permit passage of the machine therethrough, said cover being mounted permanently above said rear wall and liftable to permit the finger-piece to be passed through the slot in assembling the 10 machine and the casing, and a removable back for closing the opening in said rear wall.

3. A removable bottomless sound-deadening casing for use with a typewriting machine fixed upon a base set below the top of a desk and freely accessible only from the front, said casing having a front opening just large enough to permit the keyboard to project therethrough and a rear opening in 15 line with the front opening and permitting passage of the machine therethrough and into said casing when the latter is slid rearwardly from the front of the machine, releasable means for closing said rear opening, a cover hinged in rear to said casing above said rear opening, and releasable means for securing said casing to said machine.

4. A sound-deadening casing for a typewriting machine having a keyboard, said casing comprising a front wall having an opening just large enough to permit the keyboard to project therethrough, and a rear wall having an opening sufficiently 30 large to permit passage of the machine therethrough and into said casing, a removable back for closing said opening in the rear wall and having means for locating and holding said machine in position, means for mounting said back on said rear wall by means of one edge portion of said back, and a latch slidably mounted on said back and engageable with said rear wall for locking said back in position.

45 5. A sound-deadening casing for a typewriting machine, said casing comprising a cover part and a body part, said body part comprising a front wall, side walls and a rear wall having an opening sufficiently 50 large to permit passage of the machine therethrough and into said casing, so that said casing may be slid on said machine from the front thereof, a removable back plate for closing said opening, means for mounting said back plate on said rear wall, said means comprising hooks on said back plate adjacent one edge thereof, said rear wall having openings for receiving said hooks, projections on said rear wall, said 55 back plate having openings adjacent the opposite edge thereof for receiving said projections, and a latch slidably mounted on said back plate and engaging said projections for locking said plate in position, said 60 latch being slidable to release said plate.

6. A sound-deadening casing for a typewriting machine having a keyboard extension, said casing having a fixed front wall provided with an opening through which 70 said keyboard extension may be passed from the rear, and having locating means thereon to be engaged by said machine, said casing also having a rear insertion opening large enough to permit the passage of the machine into the casing, and a door for said 75 insertion opening.

7. A sound-deadening casing for a typewriting machine having a keyboard extension, said casing having at its front an opening just large enough to receive said extension, and locating means to engage the front 80 of the machine and assist in positioning the same in the casing, said casing also having an opening in its rear to permit passage of the typewriting machine therethrough into 85 position with the extension projecting through the front opening, and means pressing the machine against said locating means; said pressing means including a door which closes said rear opening, and 90 releasable means locking said door.

8. A sound-deadening casing for a typewriting machine comprising a carriage having a carriage-release lever projecting forwardly therefrom, said casing having a slot 95 at the front thereof through which said lever extends, and means for sealing said slot, said sealing means including a cushion-strip fixed adjacent the upper edge of said slot, and an uncushioned slot-sealing bar 100 yieldably mounted adjacent the lower edge of said slot, said bar being directly opposed to and contacting directly with said cushion-strip to seal the slot, said cushion-strip yielding locally as the lever travels along 105 the slot and said bar being depressed bodily when said lever is depressed.

9. A sound-deadening casing for a typewriting machine comprising a carriage having a carriage-release lever, said casing comprising a body part, a cover hinged at the rear to said body part and forming therewith at the front a slot through which said lever extends, and means for closing said 110 slot, said means comprising a cushion-strip fixed to said cover adjacent the upper edge of the slot, and a bar mounted on the body part adjacent the lower edge of the slot, said bar being directly opposed to and normally in engagement with said cushion-strip 115 except where separated by said lever, said carriage-release lever extending between said bar and said strip, the mounting of said bar on said body part comprising a parallel linkage to guide said bar bodily 120 downward when said lever is depressed.

10. A sound-deadening casing for a typewriting machine having a front keyboard extension, said casing having a body comprising a front wall having an opening 130

through which said extension may extend forwardly, and a rear wall having an opening in line with said front opening and sufficiently large to permit passage of the casing rearwardly over said machine, rear wall first, a releasable back for closing said opening in the rear wall, a base to support said machine and said casing, means on said base for guiding said casing into position over said machine and for assisting in holding said casing in position on said base, devices on said casing to engage said guiding means to hold said casing in position on said base, and means to retain said devices in effective relation with said guiding means.

11. A sound-deadening casing for a typewriting machine having a front keyboard extension, said casing having a body comprising a front wall having an opening through which said extension may extend forwardly, and a rear wall having an opening in line with said front opening and sufficiently large to permit passage of the casing rearwardly over said machine, rear wall first, a releasable back for closing said opening in the rear wall, a base for said casing, projections secured to said base, devices on said casing to engage with said projections, and latches on said base to engage said devices to retain them in effective relation with said projections.

12. The combination with a hood for a typewriting machine, of a base for said hood, guide-bars to locate the hood on said base, fingers at the forward ends of said guide-bars, pins projecting laterally from said hood to engage under said fingers, and spring-pressed latches pivoted on said guide-bars to engage said pins to retain them in effective relation with said fingers.

13. A sound-deadening casing for a typewriting machine having a front keyboard extension, said casing having a body comprising a front wall having an opening through which said extension may extend forwardly, and a rear wall having an opening in line with said front opening and sufficiently large to permit passage of the casing rearwardly over said machine, rear wall first, a releasable back for closing said opening in the rear wall, a base for said casing, means to establish the position of the machine on said base, means to establish the position of the casing on said base, and means to secure said casing to said base to prevent accidental displacement relative thereto.

14. A sound-deadening casing for a typewriting machine having a front keyboard extension, said casing having a body comprising a front wall having an opening through which said extension may extend forwardly, and a rear wall having an opening in line with said front opening and sufficiently large to permit passage of the

casing rearwardly over said machine, rear wall first, a releasable back for closing said opening in the rear wall, a base for said machine and said casing, said base having depressions to establish the location of the machine, devices at the sides of said casing to establish the lateral location of said casing, means to engage the back of said casing to establish its location from front to back, and means to engage said casing to prevent accidental displacement thereof on said base.

15. The combination with a typewriting machine and a sound-deadening casing therefor, of a base, means to secure the first two mentioned elements to each other, and means to secure one of the first-mentioned elements to the base.

16. The combination with a sound-deadening hood for a typewriting machine, of a base to support said hood and said machine, means to guide said hood in a horizontal movement to position over said machine, holding means on said base, and means on said hood to engage said holding means to secure said hood in position on said base.

17. The combination with a sound-deadening hood for a typewriting machine, of a base for said machine, projections secured to said base, devices on said hood to engage with said projections, and means on said base to guide said hood in a horizontal movement to position over said machine with said devices in effective relation with said projections.

18. A sound-deadening casing for a typewriting machine, said casing comprising a front wall having an opening through which the keyboard projects, two side walls and a rear wall, the rear wall having an opening to permit passage of the machine therethrough and into the casing, and a cover plate for closing said opening; said openings being in line, and said machine of a length occupying said openings simultaneously in assembling the machine with the casing.

19. The combination with a typewriting machine comprising a carriage and various operating handles extending from said carriage, of a sound-deadening casing for said machine, said casing comprising a front wall, side walls and a rear wall, the rear wall having an opening to permit the casing to be slid over said machine from the front, said front wall being beneath said handles to enable said front wall to be passed rearwardly when assembling the casing and machine, and releasable means locating said machine within said casing.

20. A sound-deadening casing for a typewriting machine having a keyboard extension, said casing having a fixed front wall provided with an opening through which said keyboard extension may be passed from the rear, and having locating means.

thereon to be engaged by said machine, said casing also having an insertion opening 5 large enough to permit the passage of the machine into the casing, and a door for said insertion opening, said door having, connected therewith, locating means to engage said machine and co-operate with the locating means on the front wall to effect proper relative positioning of said machine and 10 said casing.

21. A sound-deadening casing for a typewriting machine having a keyboard extension, said casing having a fixed front wall provided with an opening through which 15 said keyboard extension may be passed from the rear, and locating means to be engaged by said machine in its movement to pass said extension through the opening in said front wall, said casing also having an insertion opening large enough to permit the 20 passage of the machine into the casing, a door for said insertion opening and locating means co-operative with said locating means, but movable to permit disassembling 25 of the machine and casing.

22. A sound-deadening casing for a typewriting machine having a keyboard extension, said casing having a fixed front wall provided with an opening through which 30 said keyboard extension may be passed from the rear, and having locating means thereon to be engaged by said machine, said casing also having an insertion opening in the rear wall large enough to permit the passage of 35 the machine into the casing, a door for said insertion opening having locating means thereon to engage the rear of the machine and co-operate with the locating means on the fixed front wall to position said machine 40 in the casing, and means engaging said door to cause its locating means to press the machine against the front locating means.

23. A sound-deadening casing for a typewriting machine having a keyboard extension, a traveling carriage and an operating finger-piece projecting forwardly from said carriage, said casing having a fixed front wall provided with an opening through 45 which said extension may be passed from the rear, locating means to be engaged by the front of the machine during such insertion, said casing also having an insertion opening in its rear wall large enough to permit the passage of the machine into the 50 casing, a door for said insertion opening, and a cover hinged upon the casing above said rear opening to be lifted at its front to permit the insertion of the finger-piece between the front wall and the cover.

24. The combination with a typewriting machine, comprising a carriage and a handle extending from said carriage, of a sound-deadening casing for said machine, said casing having a slot therein through 55 which said handle extends, and slot-sealing

means, said slot-sealing means including a rigid bar extending along said slot, and a locally yieldable cushion opposed to said bar and contacting therewith.

25. The combination with a typewriting 70 machine, comprising a carriage and a handle extending from said carriage, of a sound-deadening casing for said machine, said casing having a slot therein through which said handle extends, slot-closing 75 means, said slot-closing means comprising a bodily yieldable rigid bar and a locally yieldable cushion contacting with said bar, and means to hold said bar yieldingly against said handle.

26. The combination with a typewriting machine, comprising a carriage and a handle extending from said carriage, of a sound-deadening casing for said machine, said casing having a slot therein through 80 which said handle extends, and slot-closing means including a rigid bar extending along said slot and a locally yieldable cushion opposed to said bar and in contact therewith, a linkage to guide said bar, and means 85 yieldingly holding said bar against said handle.

27. The combination with a typewriting machine, comprising a carriage and a handle extending from said carriage, of a sound-deadening casing for said machine, said casing having a slot therein through which said handle extends, slot-closing 95 means including a rigid bar extending along said slot and a cushion opposed to said bar, a parallel linkage to guide said bar, and a spring holding said bar against 100 said handle and said cushion.

28. The combination with a typewriting machine, comprising a carriage and a depressible carriage-release lever on said carriage, of a sound-deadening casing for said machine, said casing having a slot therein through which said lever extends, slot-closing 10 means extending along said slot, said slot-closing means comprising a cushion disposed above said lever and a rigid bar disposed beneath said lever, said bar being disposed oppositely to said cushion and depressible by said carriage-release lever, and means to guide said bar when it is being depressed.

29. The combination with a typewriting machine, comprising a frame having corner posts, of a sound-deadening casing for said machine, said casing having a releasable cover plate at the rear thereof to permit the insertion of the machine into the casing, abutments at the front of the casing to engage the front posts of the frame, and co-operating elements oppositely disposed to said abutments and carried by said releasable plate.

30. A sound-deadening casing for a typewriting machine having a main frame with 11

a keyboard extension, said casing comprising a front wall having an opening through which said extension may be passed from the rear, and a rear wall spaced from the 5 front wall sufficiently to accommodate said main frame and having an opening sufficiently large to receive the machine therethrough into said casing and so located that, as a result of such relative movement, said 10 extension will project through the opening in the front wall of the casing, a closure for said opening in the rear wall and relatively separable means for relatively locating and locking together said machine and 15 casing.

31. The combination with a typewriting machine, of a sound-deadening casing fitted thereon and having at the rear an opening for inserting and removing the machine 20 and at the front an opening to permit operation of the machine from the outside of

the casing and a set of relatively separable locators determining the position of the machine in the casing.

32. The combination with a typewriting 25 machine, of a sound-deadening casing fitted thereon and having at the rear an opening for inserting and removing the machine and at the front an opening to permit operation of the machine from the outside of the 30 casing, and means fastening the casing to the typewriting machine and effecting a predetermined relative location between said casing and said machine, said fastening means being releasable and permitting the 35 relative withdrawal of the machine through said rear opening.

JOHN WALDHEIM.
